FASTENER-SETTING MACHINE.

1,271,776.

Specification of Letters Patent.

Patented July 9, 1918.

Application filed August 20, 1914. Serial No. 857,760.

To all whom it may concern:

Be it known that I, FRED A. RUMNEY, a citizen of the United States, residing at Boston, in the county of Suffolk and State of Massachusetts, have invented certain Improvements in Fastener-Setting Machines, of which the following description, in connection with the accompanying drawings, is a specification, like reference characters on the drawings indicating like parts in the several figures.

This invention relates to improvements in machines for inserting fasteners, such as eyelets, lacing hooks or the like, in two superposed pieces of sheet material, as for example, two quarters of a boot or two sides of a corset.

In work of this character it is important that the corresponding eyelets set in the two parts of the material shall be located exactly opposite to each other and consequently it is necessary to insure that each part of the work has imparted to it feeding movements of exactly the same extent. This is particularly important in the case of work wherein a long line of eyelets is to be set, as in corsets, for if the feeding movements imparted to one part of the work vary ever so slightly from the feeding movements imparted to the other, the cumulative effect of such difference is objectionably apparent when the end of the line of eyelets is reached. An important object of the present invention is to provide improved means for guiding two pieces of sheet material as they are fed into setting position whereby the accuracy of the feeding movements is improved and uniform spacing of the eyelets in both pieces of work insured.

In duplex machines, as heretofore constructed, a guide plate has been employed having separate presser members for yieldingly holding the respective pieces of the work against its opposite sides. With such construction, it has been found difficult to secure an exactly uniform tension upon the two parts of the work and the result has been that one part is retarded more than the other so that the feeding steps have been slightly shorter in one piece than in the other. This is probably due to the fact that the work supporting plate has been disposed in a substantially horizontal position so that the weight of the lower piece of material

has tended to separate the lower presser member from the under side of the guide plate and so lessened the tension, whereas the weight of the material on the upper side of the guide plate has had the opposite effect.

I have discovered that uniform feeding movements of both parts of the work may be secured by providing a pair of oppositely disposed pressing members so constructed and arranged as to hold the two parts of the work yieldingly in engagement with each other during a part of their movement to the setting position. When the two parts of the work are thus held in contact with each other the resulting friction between their surfaces tends greatly to prevent unequal feeding of the respective pieces. Such construction is also advantageous in that it eliminates the unequal retarding of the respective parts of the work which has been found objectionable heretofore.

While the present invention relates particularly to machines for operating upon two pieces of sheet material at the same time, it is believed that work guiding means mounted for bodily yielding movement in a direction at right angles to the plane of the work have never been employed in any fastener setting machine whatever and such construction constitutes broadly an important feature of the invention.

The features above discussed and others incident to the invention will be best understood and appreciated from the following description of a preferred embodiment thereof selected for purposes of illustration and shown in the accompanying drawings, in which—

Figure 1 is a view in perspective of portions of a duplex eyeleting machine having the present invention embodied therein.

Fig. 2 is a similar view showing parts of the machine in a different position and showing also a portion of the work, and

Fig. 3 is a sectional view through the work guiding means and adjacent parts of a machine.

The general construction of the duplex eyeleting machine is disclosed in Letters Patent of the United States No. 934,066, granted Sept. 14, 1909, on an application of Goddu and in the present drawings only such portions of that machine are shown as

are necessary to the understanding of the invention. The machine frame 2 carries a normally stationary elongated guideway 4 which supports the work and directs it toward the setting position, the edges of the work being guided by a flange at the rear side of the guideway.

The operating tools of the machine are carried in a movable head or frame 6 which 10 is pivotally mounted on a journal 9 in a lever 8 mounted on the machine frame. The head 6 has imparted to it movement from front to rear in order to locate successively the punches and the setting tools in the 15 proper position to operate upon the work, and also a transverse movement for feeding the work while the setting tools engage it. The mechanism for moving the head 6 is not herein shown, as it forms no part of the present invention. The head 6 has an upper and a lower branch in each of which there are two parallel bores. The setting dies 10 are slidably mounted in the front portion of the head 6 and the punches 12 are mounted at 20 the rear of the setting die. A pair of actuating levers 13 (only one of which is shown) serve to operate successively the punches and the setting dies. The head 6 also carries a thin curved die plate 14, at the outer end 25 of which is arranged a double faced upsetting die 15, shown in Fig. 3. This upsetting die is maintained rigidly in alignment with and cooperates with the dies 10 in clenching an eyelet in each of two pieces of 30 sheet material as in the construction of the Goddu Patent No. 934,066. In distinction from this patented construction, however, one of the punch members 12 is made tubular and the other is solid so that they act as 35 a punch and die in perforating the work. The punches are arranged opposite to the space formed by the concaved curve of the die plate and in this space the punching 40 operation takes place.

45 Between the inner end of the guideway 4 and the point at which the punches operate is located a pair of work guiding members 16. The members 16 are beveled, as shown in Fig. 3, on the edges disposed toward the 50 oncoming work and are ribbed on their adjacent faces to prevent the work from sliding outwardly and away from the gaging flange of the guideway 4. Each member 16 is secured to and carried by a leaf spring 55 17. The rear ends of the springs 17 are secured to a slideable block 19 which is carried by the machine frame 2. The construction of the springs 17 is such as to hold the proximate faces of the members 16 normally 60 in contact and yieldingly tends to prevent their displacement while permitting them to separate sufficiently to admit the passage of the work.

The block 19 is provided with rack teeth 65 which mesh with a segment 18 and by

swinging this segment the block 19, together with the guideway 4 and the members 16 may be moved forwardly or rearwardly at right angles to the line of feed for varying the spread of the eyelets or their distance 70 from the edge of the work.

In operating the machine, the two parts 30 of the work are superposed, as shown in Fig. 2, and their edges laid together and against the flange of the guideway 4. The work is then pushed toward the left between the two guide members 16 until the point at which the first eyelets are to be set is located in alignment with the punches 12. When the machine is started, the punches are at 80 once operated to perforate the work and then the head 6 is moved rearwardly to bring the setting dies 10 and the upsetting die 15 into alignment with the previously punched holes. The head 6 in this rearward movement, carries with it the curved die plate 14, and the pieces of work, held stationary by the work guiding members 16, are separated by the thin plate 14 so that the double-faced upsetting die 15, which is always maintained 90 in alignment with the dies 10, is brought into alignment with the punched holes ready for the setting of the eyelets. Up to the time of their separation by this plate 14, the two parts of the work have remained in contact. The levers 13 are then operated a second time and an eyelet is inserted through each piece of work and clenched against the upsetting die 15. With the work still engaged by the setting dies, the head 6 is 100 moved toward the left, being guided in its path by the roller 5 which runs in a guideway 7. In this movement the work is drawn between the guiding members 16 which press the two pieces together and so exert an equal 105 retarding effect upon each piece, with the result that a uniform feeding movement is imparted to them both. In Fig. 2 the machine is illustrated with its parts in the positions occupied at the end of one feeding movement. As the machine continues to operate, the setting dies 10 are retracted, releasing the work so that the head 6 may be moved back to its initial position and the operations repeated.

110 It will be apparent that the shape and construction of the guiding members 16 may be varied widely, it being necessary only that they operate to press together the two parts of the work and hold the parts yieldingly 115 in contact with each other during the feeding operation.

Having thus described my invention, what I claim as new and desire to secure by Letters Patent of the United States is:—

125 1. A duplex fastener setting machine, having in combination, oppositely disposed pairs of setting dies, and work guiding means constructed and arranged to press two pieces of material into engagement with 130

each other and guide them toward setting position.

2. A duplex fastener setting machine, having in combination, oppositely disposed 5 pairs of setting dies, work guiding means constructed and arranged to press two pieces of material together at one side of setting position, and means for separating the pieces as they are advanced to setting position.

10 3. A duplex fastener setting machine, having in combination, work feeding means arranged to act upon separate pieces of sheet material, and guiding means for holding the two pieces in contact with each other at one 15 point while the feeding means act at another point.

4. A duplex fastener setting machine, having in combination, means for feeding two pieces of sheet material and setting fasteners therein, and guiding means constructed 20 and arranged to press the two pieces of material into contact with each other during their feeding movement.

5. A duplex fastener setting machine, 25 having in combination, a stationary support for superposed layers of sheet material, oppositely disposed yielding devices arranged at one end of the support for pressing the two layers into engagement with each other, 30 and work feeding means arranged to act on the work on the side of the pressing means opposite to the support while the layers of the work are so pressed.

6. A duplex eyeleting machine, having, in 35 combination, setting devices, a guideway leading toward the setting devices and terminating at a distance from said devices, and means located beyond the end of the guideway toward the setting devices for 40 pressing together two pieces of sheet material.

7. A duplex fastener setting machine, having in combination, setting devices, a guideway leading toward said devices, a 45 pair of pressing members arranged with

their proximate faces normally in contact, and yielding means tending to prevent their displacement, whereby two layers of sheet material may be equally retarded in being drawn between said members. 50

8. A duplex fastener setting machine, having in combination, fastener setting and work feeding tools, and oppositely disposed presser members movable yieldingly and mounted for free movement in unison in a 55 direction at right angles to the plane of the work.

9. A fastener setting machine having, in combination, a guideway for two superposed pieces of work, feeding devices, means for 60 pressing the two pieces of work into engagement with each other as they leave the guideway, and a movable work separating member located beyond the pressing means relatively to the direction of feed. 65

10. A fastener setting machine having, in combination, means for directing two pieces of work to setting position including yieldingly mounted members for pressing the two pieces into contact with each other, punching 70 devices arranged to punch both pieces while in contact, and means for separating the two pieces after they have been punched.

11. A duplex eyeleting machine, having, in combination, means for directing and 75 feeding two pieces of work to setting position, including yielding presser members for holding the two pieces in contact, means for punching both pieces while in contact, and means movable in a direction at right angles 80 to the line of feed for separating the two pieces where they have been punched.

In testimony whereof I have signed my name to this specification in the presence of two subscribing witnesses.

FRED A. RUMNEY.
